UNITED STATES PATENT OFFICE.

MARTIN C. BRIGHT, OF INDIANAPOLIS, INDIANA, ASSIGNOR TO BERNARD B. CARLIN, OF CHICAGO, ILLINOIS.

VENTURI-VACUUM FUEL-CONTROL SYSTEM.

Application filed October 16, 1922. Serial No. 594,895.

This invention relates to the supplying of explosion or internal combustion engines with fuel by a vacuum-feed system, especially a Venturi-vacuum fuel-control system, and has reference more particularly to a vacuum-feed system in which the well-known type of separate vacuum tank is eliminated, the invention relating also to the type of fuel-control system which has 5 single primary control by which not only the volume but the quality or character of the fuel is regulated; and the invention relates further to improvement in the type of fuel control system disclosed in Letters 10 Patent of the United States granted April 19, 1921, No. 1,374,983, and to improvement in the type of Venturi-vacuum fuel control system forming the subject of my pending application for Letters Patent of the United 15 States filed April 25, 1921, Serial No. 464,246, especially with reference to one of the modified forms of variable-action venturi referred to in said application for Letters Patent, an example of such modified 20 venturi being therein disclosed.

An object of the present invention is to provide a simple and compact fuel control system for explosion engines, and means whereby to draw liquid fuel by vacuum 30 from a reservoir under varying conditions of operation, and which shall be automatic and reliable in controlling the supply of fuel in accordance with the requirements of the engine.

Another object is to provide an improved feed reservoir for a carburetor in a fuel control system which shall be so constructed as to perform the function of a vacuum tank in a vacuum feed system, and which shall be 40 constructed of few and simple parts not liable to become deranged or to cause trouble in operation.

A further object is to provide improved means whereby to supply a carburetor directly and promptly with liquid fuel in a vacuum-feed system for explosion engines, and which shall be adapted to operate promptly in supplying fuel in response to engine suction.

A still further object is to provide an improved variable action venturi in a Venturi-vacuum fuel-control system which shall be capable of wide range of adjustment, and which especially shall be automatically adjustable, and which shall be so constructed

as to automatically control the supply of liquid fuel and air to become mixed.

A still further object is to provide an improved atomizing apparatus which shall conveniently and economically combine 60 therein an automatically adjustable Venturi tube, and which shall be capable of controlling the volume and quality of air and hydro-carbon mixture, and be economical in use.

With the above-mentioned and other objects in view, the invention consists in a unitary fuel-control system and apparatus including a combined feed-reservoir and vacuum chamber into which liquid fuel is 70 directly drawn from a main reservoir, combined in a novel manner with improved atomizing and carbureting apparatus, the complete structure being so designed as to be adapted to advantageously comprise an 75 important feature of a fuel-control system and especially a Venturi-vacuum fuel control system; and, the invention consists also further in certain novel parts, and in the 80 combinations and arrangements of parts or features, as hereinafter particularly described and further set forth in the claims appended hereto.

Referring to the drawings,—Figure 1 is a 85 side elevation of the new fuel-control system conveniently but not arbitrarily arranged in connection with an automobile which is indicated fragmentarily by broken lines, illustrating a practical application of the invention; Fig. 2 is a vertical central 90 section of the principal structure involved in the invention, on an enlarged scale, parts of which are arranged relatively to other parts conveniently rather than arbitrarily; Fig. 3 is a top plan of the essential portions of Fig. 1; Fig. 4 is a section approximately on the line IV—IV in Fig. 2; Fig. 5 is a section approximately on the line V—V 95 in Fig. 2, looking upward; Fig. 6 is a fragmentary vertical central section showing details of controlling apparatus which may be used in the system, being an example of the application of one form of controlling valve which may be variously modified; Fig. 7 is a section approximately on the line VII—VII in Fig. 6; Fig. 8 is a front view 100 of the controlling valve and its chest, the valve being in a different position from that in Figs. 6 and 7, and partially in section; Fig. 9 is a section approximately on 105

the line IX-IX in Fig. 7; and, Fig. 10 is a section approximately on the line X-X in Fig. 8.

In the various figures of the drawings 5 similar reference characters indicate corresponding or like elements or features of construction herein particularly referred to.

In the drawings the numeral 1 indicates generally an automobile or motor vehicle, 2 10 the explosion engine thereof which has the conventional or other suitable intake manifold 3, a low-level main fuel reservoir or tank 4 being carried by the automobile, commonly at the rear of the vehicle body.

15 The invention as preferably constructed comprises a mixing tube 5 which is secured to the intake manifold or pipe 3 in such manner as may be desired, preferably in vertical position, and it rotatively supports 20 a shaft 6 that extends through the tube and has a throttle valve 7 of the butterfly type secured thereto within the tube, and a controlling arm or lever 8 is secured to the shaft at the outer side of the tube. A vacuum 25 chamber is connected with the mixing tube and comprises a hollow cylindrical portion 9 that extends from the tube and is preferably less in diameter than the tube internally so that the upper end thereof forms a stop 30 shoulder 10, opposite to which a suitable distance therefrom a stop or stops 11, 11', are secured in the wall of the mixing tube in the region of the vacuum chamber. The 35 vacuum chamber includes a feed-chamber combined therewith which comprises a wall 12, a top 13 and a bottom 14, the top being annular and extending about the cylindrical portion 9 and being fixed thereto. The wall 12 has an inlet aperture 15 therein. The 40 bottom 14 also is annular and a cylindrical wall portion 16 extends through it and is fixed thereto and so as to constitute an annular partitional wall 17 in the feed chamber which is designed to hold liquid fuel, as a 45 portion of a feed-reservoir, the wall terminating a suitable distance from the lower end of the wall portion 9. A shifting Venturi tube 18 of novel form is provided which is externally cylindrical and arranged to 50 mutually operate in the vacuum chamber, being guided by the wall portions 9 and 16 and the wall extension 17. The Venturi tube constitutes a port-shifting venturi and has a collar portion or head 19 that rests upon 55 the shoulder 10 to limit the downward movement of the tube. The lower portion of the Venturi tube has a tapered inner wall face 20, the outer end of which is the larger and preferably terminating in a concave counter-bore 21 extending from the lower end of the tube, the upper portion of the tube having a tapered or inclined inner wall face 22, so that the interior of the upper portion is 60 funnel-like in shape in which a flow of fluid 65 is expanded in its passage to the mixing

tube. The wall of the Venturi tube has a horizontal feed port or preferably several ports 23 arranged so that the outer end of the port shall be slightly higher, or a portion of the port higher, than the top of the 70 wall 17 to conduct the liquid fuel to the interior of the Venturi tube, so that the tube may be instrumental in atomizing the fuel. The wall of the Venturi tube has also another feed port or several ports 24 at a relatively lower-level therein and closed by the 75 wall 17 when the tube is set at its lowest level. All the ports extend from the periphery to the tapered inner face 20 of the wall of the Venturi tube. Preferably the 80 lower ports are larger diametrically than the upper ports or are greater in number. The lower end of the wall portion 16 has a spider ring 25 suitably secured thereto, preferably by means of screw threads so as to be adjusted 85 and also removable, and it has arms 26 supporting a hub 27 to which a stem 28 is secured, the stem having a shank portion 29 extending through the hub and having a threaded nut 30 thereon engaging the under 90 side of the hub. The stem has an atomizer head 31 on its top that has a tapered exterior 32, so that the head is frustum shaped, the lower portion of the head being greater in diameter than the stem and curved or bevelled so as to deflect air outward in the counter-bore 21 into which the lower portion 95 of the head extends, the head being partially in the tapered portion 20, the top of the head preferably being on the level of the axis of 100 the port 23. The head and the stem are hollow so as to constitute portions of a vacuum-conduit which preferably has an extension 33 projecting from the top of the atomizer head, and the extension preferably 105 is an integral portion of a tube 34 inserted tightly in the head and the stem 28 and extending beyond the shank portion 29 so as to constitute a nipple 35 to which a conduit 110 extension 36 is connected.

115 The fuel-control system has a novel vacuum chamber and feed-reservoir comprising a bottom 37 and a wall 38 thereon, the wall being suitably secured or fixed to the wall 12 and having an outlet aperture 39 therein connected with the aperture 15, so that the chamber extending to the wall 17 constitutes an extension of the reservoir chamber. The middle portion of the bottom 37 has a guide rod 40 fixed thereon, and a suitable float 41 is arranged in the reservoir and has a central guide sleeve 42 receiving the rod 40, the float being adapted to freely float in the liquid fuel received into the reservoir. The feed-reservoir has a head or 120 cover thereon which preferably consists of a removable head 43 having a fulcrum arm 44 on its under side that supports a pivot 45 to which a controlling lever 46 is connected that extends to the top of the float. 125

A casing 47 is suitably secured in an aperture in the head 43 and it has a neck 48 thereon, a duct 49 extending through the casing and the neck. The lower portion of the casing has a counterbore 50 and a valve seat 51 extending therefrom to the duct, and a supply conduit 52 is connected with the neck 48 and also with the reservoir 4. A valve 53 is arranged to co-operate with the valve seat 51 and it has a stem 54 movably arranged in a hollow guide 55 comprising a portion of a spider 56 secured in the counterbore, the valve stem being located so as to be controlled by the lever 46 to close the duct when the reservoir contains the desired quantity of fuel. The upper portion of the vacuum chamber in the feed-reservoir is provided with a vacuum dome 57 that is preferably a detachable part of the head 43 and covers an opening 58 in the head. The top of the dome has a duct 59 therein and preferably the under side of said top has a projection 60 through which the duct extends, the outer portion of said top having a neck 61, the duct extending through the neck, and a suction conduit 62 is connected to the neck. Preferably the vacuum dome has a baffle comprising a base 63 and a hollow cone 64 therein to prevent splashing of the liquid fuel into the duct 59, the base being arranged on the head 43 so that the baffle shall cover the opening 58. The base of the baffle has an air-duct 65 therein which preferably is located nearly to the middle of the reservoir head, so as to be away from the wall of the reservoir against which the liquid fuel may surge during operation of the motor vehicle. Ample space is left in the dome above the baffle to prevent the formation of a narrow or rapid stream through the dome, and the space is divided preferably by means of a tube 66 interposed between the top of the dome and the baffle cone and having a suitable number of apertures 67 therein, practically constituting a screen to prevent atoms of liquid from entering the duct 59. The conduit 62 is suitably connected with the mixing tube 5, and it is designed that the conduit 36 may be connected with the conduit 62 according to the requirements of operation of the engines. In some cases it may be designed that suction may automatically occur through the conduit 36 and the conduit 62 at high speed of the engine, and through the mixing tube and conduit 62 only at low speed of the engine, but preferably the mutable action in the conduit 36 is governed by a controlling valve operating automatically on operation of the primary controller and the throttle valve.

As an illustration of suitable valve controlling means, which may be similar to that described in said Letters Patent No. 1,374,983, for controlling the action due to

suction through the conduit 36 following the action due to suction primarily occurring directly through the mixing tube and the conduit 62, a valve chest is provided on the mixing tube and comprises a body wall 70 fixed to the mixing tube and a cover 69 removably secured to the wall, the chest having a plane valve seat 70 therein and a port 71 extending from the face of the seat to the interior of the mixing tube. The inner side of the cover 61 has a projection 72 thereon and arranged at a suitable distance away from the port 71, and the conduit 36 is connected to the cover so as to have communication with a port 36' that extends 75 through the projection, the end of the projection having a valve seat face presented opposite to the seat 70 at a suitable distance therefrom. The conduit 62 is connected also with the cover 69 so as to have 80 communication with a duct 62' which extends through the cover, the duct being constantly open, so that in some cases there may be communication through the interior of the valve chest between the conduits 36 85 and 62, in such cases the valve chest being merely a convenient connection between the conduits, the port 71 being constantly open. But preferably a plate valve 73 is provided which is connected to a pivot 74 secured to 90 the valve seat 70, the valve being adapted to operate on the seat to close the port 71 or to open the port and to cover the port 36'. The valve preferably has a projection 95 100 engaged by a spring-projected plunger 76 to accelerate the movement of the valve after having been started in either direction. The back of the valve has a laterally extending slot 77 whereby to move the valve, and a crank disk 78 is rotatively arranged 105 in a recess 79 extending from the valve seat 70, the disk being turned by means of a key 80 on the end of the throttle valve shaft 6 and extending into a slot in the back of the disk, the front of the disk having a crank pin 81 thereon that operates in the slot 77. Preferably a spring 82 is interposed between the cover 69 and the valve 73 to hold the valve to its seat. It will be seen that the valve 73 is controlled by the 110 throttle lever 8.

When the fuel has become exhausted and it becomes difficult to start an explosion engine, a supply may be obtained from the reservoir 4 by means of a suitable suction pump connected with the system so as to create vacuum in the feed-reservoir, and such pump may comprise a cylinder 83 connected with the conduit 62 and having a suitable operating rod 84 provided with a handle 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 uum from the main reservoir, the engine is started in the usual manner, the throttle valve 76 properly adjusted to admit sufficient fuel to the engine for slow speed, the valve 73 if present being set to close the conduit 36. The level of the fuel in the feed reservoir should be approximately at the top of the wall 17, permitting the suction produced by the engine pistons to draw fuel through the port 23 and into the Venturi tube to become atomized therein as a result of atmospheric air being drawn by suction past the atomizer head 21 and into and through the Venturi tube, the resultant carbureted air becoming mixed in passing through the mixing tube 5 to the engine. As the air enters the lower end of the vacuum chamber some of the air is deflected by the lower portion of the atomizer head, and the air is gathered 20 into the tapered portion 20 into the form of a thin annular current and directed inward to the relatively thin extension 33 of the atomizer head, and thereby partially spread out towards the wall of the flaring upper portion of the Venturi tube, and tending to thoroughly atomize and mix the fuel with the air. The engine being in operation at slow or moderate speed, suction occurs through the mixing tube and the port 71 and also through the conduit 62, resulting in the creation of vacuum in the feed-reservoir and suction through the conduit 52, the valve 53 being open so that fuel is drawn from the main reservoir and into the feed reservoir until the float 41 rises sufficiently to operate the lever 46 which closes the valve, thus preventing an over-supply that might cause flooding of the engine. The proper level of the fuel in the feed-reservoir is maintained automatically as the float rises and falls in the liquid fuel and controls the intake valve 53 when the engine requires an increased supply of fuel, the throttle valve being further opened to admit the fuel to the engine, increasing suction in the Venturi tube causing the tube to be drawn upward to admit the fuel, first through the port 23 which becomes fully opened, afterwards through the port 24 also when it is carried up sufficiently to permit fuel to enter it from the top of the wall 17. When the shifting Venturi tube is fully drawn up against the stops 11 the port 24 is fully opened to receive the liquid fuel, the port 23 being still uncovered below the end of the cylinder portion 9, becomes a suction-duct to automatically increase vacuum for lifting the fuel, and permitting gaseous vapor that may rise from the feed chamber to pass through the port 23 and become mixed with the product in the Venturi tube. As the throttle valve 7 is further opened the valve 73 is moved from the port 36 and over to the port 71 to close direct communication with the mixing tube, permitting the strong suction in the Venturi

tube to cause suction through the conduit 36 and the valve chest and through the conduit 62 desired to produce a greater degree of vacuum in the feed-reservoir to insure increased supply of fuel as may be needed by the engine performing increased duty. After the throttle valve has been adjusted to reduce the supply of fuel the suction below the throttle valve is decreased and permits the Venturi tube to again descend, the conduit 36 becoming closed by the consequent shifting of the valve 73 so that the engine may be supplied as before with sufficient fuel for slow speed.

Having thus described the invention, what is claimed as new is:

1. An explosion engine fuel control system including a fuel-feed reservoir having a lateral feed-chamber, a fuel-inlet for the reservoir, means in the reservoir to automatically control the fuel-inlet, a shifting Venturi tube having a port to conduct fuel from the feed-chamber and into the tube, an atomizing device in the Venturi tube, a mixing tube, a section conduit having connection with the reservoir, an alternating vacuum conduit extending from the interior of the Venturi tube, and cooperating means for controlling the shifting Venturi tube and for alternatively connecting the suction conduit with the mixing tube and the vacuum conduit with the suction conduit.

2. A fuel-control system including a fuel-feed reservoir having a lateral feed-chamber connected therewith, the upper portion of the reservoir being a chamber for vacuum, a vacuum chamber connected with the upper portion of the feed-chamber, a mixing tube connected with the vacuum chamber, a shifting Venturi tube vertically movable in the vacuum chamber and the feed-chamber and having ports on different levels to control the passage of liquid and gaseous fuel successively from the feed-chamber and into the Venturi tube and the mixing tube, means including a suction conduit contributing to create a measure of vacuum in the fuel-feed reservoir, the vacuum being increased through the feed-chamber and the ports, and means automatically controlled rendered effective by suction in the Venturi tube and the mixing tube and shifting of the Venturi tube to contribute to create a relatively greater measure of vacuum through the suction conduit in the fuel-feed reservoir.

3. An explosion engine fuel-control system including a fuel-feed reservoir having a lateral feed-chamber, a vacuum-chamber connected with the feed-chamber, a shifting Venturi tube operating vertically in the feed-chamber and the vacuum-chamber and having ports on different levels therein to successively conduct fuel and vapor from the feed-chamber and into the tube, the ports contributing to increase vacuum in the reser-

- voir above the fuel, an atomizer head in the Venturi tube and bodily supported by means of the feed-chamber wall below the tube, a suction conduit connected with the fuel-feed reservoir, and a Venturi-vacuum conduit extending from the inside of the Venturi tube and through the atomizer head and having means for a connection with the suction conduit.
- 5 4. An explosion engine fuel-control system including a fuel-feed reservoir having a lateral feed-chamber, a mixing tube, a suction conduit connected with the reservoir, a port shifting Venturi tube operating vertically in the feed-chamber and discharging into the mixing tube, the Venturi tube having a port therein to conduct fuel from the feed-chamber and into the tube and having also a relatively higher port to conduct air 10 from the upper portion of the reservoir through the upper portion of the feed-chamber and into the Venturi tube for creating vacuum in the reservoir upon ascent of the Venturi tube, a fuel-inlet valve for the reservoir, a buoyant device in the reservoir to control the fuel-inlet valve, an atomizer head arranged in the Venturi tube and bodily supported stationarily by means of the feed-chamber wall below the tube, and means to 15 constitute a connection of the suction conduit with the mixing tube.
- 5 5. An explosion engine fuel-control system including a fuel-feed reservoir having a lateral feed-chamber, a mixing tube, a port shifting Venturi tube operating vertically in the feed-chamber and discharging into the mixing tube, the Venturi tube having a plurality of ports therein to conduct fuel and air from the feed-chamber and into the tube, a suction conduit connected with the upper 20 portion of the reservoir, an atomizer head stationarily arranged in the lower portion of the Venturi tube, a Venturi-vacuum conduit extending from the inside of the Venturi tube above and through the atomizer head, means to constitute a connection of the suction conduit with the mixing tube, and means for functionally connecting the Venturi-vacuum conduit with the suction conduit.
- 5 6. An explosion engine fuel-control system including a fuel-feed reservoir having a lateral feed-chamber, a vacuum chamber connected with the feed-chamber, a fuel-inlet valve in the upper portion of the reservoir, a float in the reservoir to control the valve, a freely movable Venturi tube in the vacuum chamber and guided in and extending through the feed-chamber, the Venturi tube having a port therein to conduct fuel from the feed-chamber and into the tube, an atomizer head supported to be stationary in the Venturi tube, a suction conduit connected with the upper portion of the fuel-feed reservoir, and a Venturi-vacuum con- 25
- duit extending from the inside of the Venturi tube and through the atomizer head and having means for automatic connection with the suction conduit.
7. An explosion engine fuel-control system including a fuel-feed reservoir having a lateral feed-chamber, a fuel-inlet for the reservoir, means in the reservoir to automatically control the fuel-inlet, a shifting Venturi tube in the feed-chamber and having a port to conduct fuel from the feed-chamber and into the tube, an atomizing device in the Venturi tube, a mixing tube having a suction port connected therewith, a suction conduit having connection with the upper portion of the fuel-feed reservoir, a Venturi vacuum conduit extending from the interior of the Venturi tube, and means for controlling the functioning of the suction port and the Venturi vacuum conduit 30 and to connect one or the other with the suction conduit.
- 75 8. An explosion engine fuel-control system having a fuel-feed reservoir, a mixing tube, a throttle valve in the mixing tube, a shifting Venturi tube automatically controlled by suction through the mixing tube and having separate ports arranged to successively conduct fuel from the reservoir and into the tube upon ascent of the tube, an atomizing device in the Venturi tube, a valve chest having a port extending therefrom and into the mixing tube, a suction conduit connected with the valve chest and the upper portion of the fuel-feed reservoir, a Venturi-vacuum conduit extending from the interior of the Venturi tube to the valve chest, and a valve means in the chest controlled by the throttle valve to alternately close the port and the Venturi-vacuum conduit.
- 85 9. In a fuel-control system, the combination with a fuel-feed chamber, and atomizing apparatus connected with the chamber, of a shifting fuel-feeding Venturi tube in said chamber, a feed-reservoir connected with said chamber and having a head provided with a capacious vacuum dome having free communication with the feed-reservoir, the dome having a deflecting baffle therein, a suction conduit connected with the dome above said baffle, and means in the feed-reservoir separate from the dome to control admission of fuel into the feed-reservoir.
- 90 10. In an explosion engine fuel-control system, the combination of a fuel-feed reservoir with a fuel-inlet in its top, a vacuum dome on the top of the reservoir separate from the fuel-inlet, a mixing tube, a suction conduit connected with the vacuum dome, a feed-chamber on one side of the reservoir in connection therewith, a Venturi tube vertically movable in the feed-chamber to discharge into the mixing tube and having 100

ports to conduct fuel and air from the feed-chamber and into the tube, an air-feeding atomizer head stationarily arranged in the Venturi tube to co-operate therewith and having support below the tube, a Venturi-vacuum conduit having an open end in the Venturi tube above the atomizer head, and valve means to connect the suction conduit with the mixing tube or the Venturi-vacuum conduit.

11. In an explosion engine fuel-control system, the combination of a fuel-feed reservoir having a feed-chamber, a fuel-inlet for the reservoir, means in the reservoir to automatically control the fuel-inlet, an operative port-shifting venturi to conduct liquid fuel and air from the feed-chamber and into the

venturi, air-feeding and atomizing means in the venturi, a mixing tube, a throttle valve to regulate suction through the mixing tube 20 and the venturi, a valve chest with a suction port connected with the mixing tube above the throttle valve, a suction conduit connected with the reservoir and also with the valve chest, a Venturi-vacuum conduit subjected to influence of the Venturi action and connected with the valve chest, and means in the valve chest automatically controlled with the throttle valve to connect the Venturi-vacuum conduit with the suction conduit. 25

In testimony whereof, I affix my signature on the 13th day of October, 1922.

MARTIN C. BRIGHT.
